(57) **CLAIM**

The ornamental design for shoulder support system for tactical vest, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a perspective view of a shoulder support system for a tactical vest, showing my new design;

FIG. 1.2 is another perspective view thereof;

FIG. 1.3 is a real elevation view thereof;

FIG. 1.4 is another perspective view thereof;

FIG. 1.5 is a front elevation view thereof;

FIG. 1.6 is another perspective view thereof; and,

FIG. 1.7 is another elevation view thereof shown in an unclaimed environment.

The design comprises the shoulder support system for a tactical vest; Reproduction 1.7 illustrates the shoulder support system used with a tactical vest; the tactical vest in design 1.7 is disclaimed protection.
